CLAIM

The ornamental design for a merchandiser with multi-tier shelving, as shown and described.

DESCRIPTION

FIG. 1 is a perspective view of a merchandiser with multi-tier shelving having a curved glass profile configuration and a top and a bottom tier shelf, according to a first embodiment of the design.

FIG. 2 is a side view of the merchandiser of FIG. 1, according to the first embodiment of the design.

FIG. 3 is a front view of the merchandiser of FIG. 1, according to the first embodiment of the design.

FIG. 4 is a rear view of the merchandiser of FIG. 1, according to the first embodiment of the design.

FIG. 5 is a top view of the merchandiser of FIG. 1, according to the first embodiment of the design.

FIG. 6 is a perspective view of a merchandiser having a flat glass profile configuration and a top and a bottom tier shelf, according to a second embodiment of the design.

FIG. 7 is a side view of the merchandiser of FIG. 6, according to the second embodiment of the design.

FIG. 8 is a front view of the merchandiser of FIG. 6, according to the second embodiment of the design.

FIG. 9 is a rear view of the merchandiser of FIG. 6, according to the second embodiment of the design.

FIG. 10 is a top view of the merchandiser of FIG. 6, according to the second embodiment of the design.

FIG. 11 is a perspective view of a merchandiser having an extended curved glass profile configuration and a top and a bottom tier shelf, according to a third embodiment of the design.

FIG. 12 is a side view of the merchandiser of **FIG. 11**, according to the third embodiment of the design.

FIG. 13 is a front view of the merchandiser of **FIG. 11**, according to the third embodiment of the design.

FIG. 14 is a rear view of the merchandiser of **FIG. 11**, according to the third embodiment of the design.

FIG. 15 is a top view of the merchandiser of **FIG. 11**, according to the third embodiment of the design.

FIG. 16 is a perspective view of a merchandiser having a bowed glass profile configuration and a top and a bottom tier shelf, according to a fourth embodiment of the design.

FIG. 17 is a side view of the merchandiser of **FIG. 16**, according to the fourth embodiment of the design.

FIG. 18 is a front view of the merchandiser of **FIG. 16**, according to the fourth embodiment of the design.

FIG. 19 is a rear view of the merchandiser of **FIG. 16**, according to the fourth embodiment of the design; and,

FIG. 20 is a top view of the merchandiser of **FIG. 16**, according to the fourth embodiment of the design.

The broken line portions do not form part of the claimed design, and are depicted for illustrative purposes only.
